UNITED STATES PATENT OFFICE.

ALEXANDER W. TABERT, OF WEST ALLIS, AND JUNIUS E. TISDALE, OF MILWAUKEE,
WISCONSIN; SAID TISDALE ASSIGNOR TO SAID TABERT.

SPIKE-STRAIGHTENER.

1,389,228.

Specification of Letters Patent. Patented Aug. 30, 1921.

Application filed May 14, 1920. Serial No. 381,317.

To all whom it may concern:

Be it known that we, ALEXANDER W. TABERT and JUNIUS E. TISDALE, citizens of the United States, residing at West Allis and Milwaukee, respectively, in the county of Milwaukee and State of Wisconsin, have invented certain new and useful Improvements in Spike-Straighteners, of which the following is a specification, reference being had to the accompanying drawing, forming a part thereof.

The main objects of this invention are to straighten and restore to original and proper form, used or bent railway spikes or the like, and thereby reclaim otherwise useless spikes which have heretofore been classed as scrap iron and represent a large item of expense and loss in railway repair work and maintenance, and to avoid the necessity of providing and keeping a large stock of spikes on hand and carrying more than are required from place to place where track repairs are to be made.

It consists in the construction, arrangement and combination of parts as herein-after particularly described and pointed out in the claims.

In the accompanying drawing like characters designate the same parts in the several figures.

Figure 1 is a plan view of a spike straightener embodying the invention; Fig. 2 is a vertical longitudinal section thereof on the line 2—2, Fig. 1; Fig. 3 is a vertical cross section on the line 3—3, Fig. 2; Fig. 4 is a plan view of a modified construction of the device; and Fig. 5 is a side elevation of the same.

The straightener, as shown in Figs. 1, 2 and 3, comprises relatively fixed and movable jaws 1 and 2, which are hinged together adjacent their lower ends by a pin 3.

The fixed jaw 1, is formed at its lower end with a flange or extended base 5, for supporting it in an upright position on a plank or block 6, to which it may be fastened by spikes 7, as shown in Fig. 2.

The jaws when closed, form one or more vertical cavities or matrices 9 and 10, corresponding in shape with the bodies of spikes to be straightened, and opening at the upper ends of the jaws. These cavities may be formed partly in each jaw or entirely

in one jaw. As shown in Figs. 1, 2 and 3, they are formed by grooves or channels entirely within the fixed jaw 1, the movable jaw 2 serving as a closure therefor, or forming one side only of the quadrangular cavities or matrices 9 and 10.

At the upper open ends of the cavities 9 and 10 the jaws are shaped to conform to the under sides of the spike heads, so that when the spikes are driven into the cavities, the heads will be trued and brought into proper relation to the bodies.

Adjacent its upper end and in its outer side opposite the cavities 9 and 10, the fixed jaw 1 is formed with a transverse semi-cylindrical seat or fulcrum bearing 12.

A lever arm or handle 14 is formed or provided at one end with a transverse cylindrical trunnion 15, fitted to turn in the seat or bearing 12, in which it is held by spaced lugs or keepers 16, formed on or attached to the jaw at each side of the arm or handle, thereby pivotally connecting the arm or handle with the jaw.

The trunnion 15 is formed or provided at the ends with aligned pintles 18, which are eccentric to the axis of the trunnion.

The movable jaw 2 is connected with the pintles 18 on each side of the straightener by links 20 and a pin 21 passing through a transverse hole in said jaw parallel with the trunnion 15.

To facilitate removal of the straightened spikes from the channels or cavities 9 and 10, particularly when they are formed entirely within the fixed jaw 1, ejector pins 22 are fitted and guided in openings between the cavities and the seat or bearing 12, and the trunnion 15 is formed with recessed cams 23, which by engagement with the pins, thrust the spikes laterally out of the cavities when the lever arm or handle 14 is turned upwardly and the straightener is opened, as indicated by dotted lines in Fig. 2.

To prevent accidental removal and loss of the ejector pins from the jaw 1, they are formed at their outer ends with heads, and the outer ends of the holes or openings in which the pins are fitted are counterbored to receive the heads, so that they will not interfere with the operation of the trunnion 15 in opening the jaws or straightener.

The straightener is formed with a transverse clearance hole or opening 25, intersecting the lower ends of the cavities or matrices 9 and 10, to facilitate the removal 5 therefrom of scale and dirt.

The straightener may be provided with one or more cavities or matrices for operation on spikes of any shape and size, or of different shapes and sizes.

10 In the operation of the straightener, the lever arm or handle 14 being turned down and the movable jaw 2 closed against the fixed jaw 1, as shown in Figs. 1 and 2, the points of the spikes to be straightened are 15 inserted in the upper ends of the grooves or cavities 9 and 10, and are driven into place therein, as shown in Fig. 2, with a sledge or heavy hammer, thereby straightening the bodies and truing the heads relative to the bodies. The centers of the pintles 18 being turned down slightly below 20 the axis of the trunnion 15 in closing the straightener, the movable jaw 2 is thereby locked and held in its closed position against 25 the fixed jaw 1, so that it will not be forced open by driving or forcing the spikes into the grooves or cavities 9 and 10.

After the spikes have thus been driven or forced into place and straightened, the 30 lever arm or handle 14 is turned upward, thereby swinging the jaw 2 away from the jaw 1 and opening the straightener. In opening the straightener the cams 23 force the ejector pins 22 inwardly and thrust the 35 spikes from the grooves or cavities 9 and 10.

Referring to Figs. 4 and 5, illustrating a modification of the tool, the matrix grooves, channels or cavities 9 and 10 are formed in dies 27 which are removably 40 fitted in dovetail or undercut recesses in the jaws 1 and 2 and may be renewed or exchanged for others having matrix grooves, channels or cavities of different sizes or shapes without throwing away or duplicating the entire jaws.

45 The fixed jaw 1 is formed below the movable jaw 2 with another base flange or foot 5, to which the movable jaw is hinged on the opposite side of the central vertical plane 50 between the jaws from the fixed jaw, so that a clearance space or opening is afforded below the dies not only for the escape of scale and dirt from the matrix grooves or cavities, but also for the removal of straightened spikes which will fall between the lower 55 ends of the jaws when they are opened and through an opening formed for the purpose in the base on which the straightener is mounted.

60 To relieve the hinge connection between the jaws from the downward thrust and strain exerted on the movable jaw in driving spikes into the matrix grooves or cavities, the fixed jaw 1 may be formed on the 65 sides with shoulders 29 for engagement with

corresponding overhanging shoulders 30 on the sides of the movable jaw 2, as shown in Fig. 5.

When a matrix or cavity for spike bodies is formed partly in each jaw or die, as 70 shown at 9 in Fig. 4, the jaws or dies are provided with an interlocking tongue 32 and groove 33 to prevent lateral displacement of one jaw or die relative to the other and undue strain on the hinge connection 75 between them by driving or forcing bent spikes into the straightening matrix or cavity.

To facilitate the construction of the tool or straightener the links 20 may be connected with the jaw 2 by means of pintles or studs 35, cast on the jaw in place of the pin 21, shown in Figs. 1 and 2, for which a hole has to be drilled through the jaw, and the hinge connection between the jaws may consist of pintles or studs 36, cast on the jaw 2 and fitted into slotted ears 37 cast on the extended base of the jaw 1.

The pintles or studs 36 are flattened on opposite sides so as to pass through the contracted openings into the ears 37 when the jaw 2 is turned down into a horizontal position in assembling the parts of the straightener and to interlock with the ears when the jaw is turned up into position to 95 be connected with the links 20.

A curved ratchet pawl or catch 39 pivoted to the jaw 1 and extending upwardly and outwardly therefrom through a slot in and engaging with the lever arm or handle 100 14, prevents said arm or handle from being jarred upwardly by driving spikes into the straightener and from accidentally releasing the movable die and permitting it to open prematurely.

105 In other respects the tool shown in Figs. 4 and 5 is substantially like that shown in Figs. 1, 2 and 3, in construction and operation.

110 In many cases bent spikes may be straightened without driving by simply placing them in position between the jaws when the straightener is open and then closing the movable jaw 2 with the lever arm 14 against the fixed jaw 1, thereby forcing the spikes 115 into the cavity or matrix 9 or 10 formed by the closed jaws.

120 Various modifications in the details of construction and arrangement of parts other than those hereinbefore described may be made without departure from the principle and scope of the invention as defined in the following claims.

125 We claim:

1. In a spike straightener the combination of relatively fixed and movable jaws forming when closed a longitudinal matrix of the shape in cross section of spikes to be straightened and hinged together adjacent one end of the matrix, a lever pivotally 130

connected with the fixed jaw and provided with pintles eccentric to its pivot axis, and links pivoted to the movable jaw and connecting it with the pintles of the lever on opposite sides of the fixed jaw.

2. In a spike straightener the combination of relatively fixed and movable jaws hinged together adjacent their lower ends and forming when closed a vertical cavity corresponding in cross section with the shape of the bodies of spikes to be straightened and open at the upper ends of the jaws, the fixed jaw being formed adjacent its upper end with a transverse bearing, a lever having at

10 one end a transverse cylindrical trunnion fitting and normally confined in said bearing and provided at the ends with alined pintles eccentric to its axis, and links pivoted to the movable jaw and connecting the 20 pintles therewith on each side thereof.

3. In a spike straightener the combination of two jaws hinged together at one end and forming when closed a matrix corresponding in shape with the bodies of spikes to be straightened and open at the other end of the jaws, one of the jaws having a transverse bearing, a lever having at one end a transverse trunnion seated and rotatable in said bearing and provided at the ends with eccentric pintles, links connecting the pintles with the other jaw on each side of the straightener, a cam formed in the lever trunnion, and an ejector pin guided in an opening in one jaw between the cam and matrix.

35 4. In a spike straightener the combination of relatively fixed and movable jaws hinged together adjacent their lower ends and forming when closed a vertical matrix corresponding in shape with the bodies of spikes to be straightened and open at the upper end of the straightener, a transverse clearance opening intersecting the lower end of the matrix, a lever arm pivotally connected at one end with the fixed jaw adjacent its upper end and provided with transverse alined pintles eccentric to its pivot axis, and links pivoted to the movable jaw and connecting it with the pintles.

5. In a spike straightener the combination of relatively fixed and movable jaws hinged together adjacent one end thereof and forming when closed a longitudinal cavity corresponding in shape with the bodies of spikes to be straightened and opening at the other end of the jaws, the fixed jaw having a transverse fulcrum bearing, a lever having a transverse trunnion fitted to turn and con-

fined in said bearing and provided at the ends with alined eccentric pintles, and links pivoted to the movable jaw and connecting it with the pintles which in closing the jaws are arranged to pass beyond straight lines intersecting the axis of the trunnion and the pivot connections between the links and the movable jaw to hold the jaws closed.

6. In a spike straightener the combination of a relatively fixed upright jaw having an extended base at the lower end and formed in one side with a transverse fulcrum bearing and in the other side with a vertical matrix channel extending through the upper end of the jaw, a movable jaw hinged at its lower end to the fixed jaw adjacent its lower end and adapted to close over the matrix channel therein, a lever arm having at one end a transverse cylindrical trunnion fitted to turn in said fulcrum bearing and provided at the ends with eccentric pintles and between its ends with a recessed cam, links connecting the pintles with the movable jaw 80 on each side thereof and an ejector pin guided and held in an opening through the fixed jaw between the matrix channel and the cam in the trunnion.

7. In a spike straightener the combination of jaws hinged together adjacent one end and formed in their inner sides adjacent their other ends with longitudinal undercut recesses, dies removably fitted in said recesses and forming when the jaws are closed 90 a matrix cavity corresponding in cross section with the shape of the bodies of spikes to be straightened and opening at the upper ends of the jaws, and a lever arm fulcrumed on one jaw and connected with the other for 95 closing them and holding them closed.

8. In a spike straightener the combination of relatively fixed and movable jaws hinged together adjacent their lower ends and forming when closed a vertical matrix cavity corresponding in shape with the bodies of spikes to be straightened, the jaws being formed with shoulders adapted by engagement with each other to relieve the hinge connection between the jaws from the thrust 105 of spikes driven into said cavity, a lever having a transverse fulcrum bearing in the fixed jaw and provided with eccentric pintles, and links connecting the pintles with the movable jaw.

In witness whereof we hereto affix our signatures.

ALEXANDER W. TABERT.
JUNIUS E. TISDALE.
